CAREL T. TORRESEN, OF CLEVELAND, OHIO, AND CHARLES G. ROTH, OF FORD CITY, MICHIGAN.

CARBURETOR.

Application filed October 29, 1921. Serial No. 511,309.

To all whom it may concern:

Be it known that we, CAREL T. TORRESEN and CHARLES G. ROTH, citizens of the United States, residing at Cleveland, Ohio, and Ford City, Michigan, respectively, in the counties of Cuyahoga and Wayne, respectively, have invented a certain new and useful Improvement in Carburetors, of which the following is a full, clear, and exact description, reference being had to the accompanying drawings.

This invention is concerned particularly with simplification in carburetors and has for one of its objects the provision of a cheaply constructed carburetor of very few parts and easily set adjustments and so arranged that a proper fuel mixture is attained irrespective of the speed at which the engine operates.

In connection with the adjustment of carburetors in use at the present time, much difficulty has been experienced in obtaining an adjustment which provides an efficient mixture for all speeds of the engine.

Frequently complex air and liquid mutual adjustments are necessary, and sometimes two spray nozzles and intricate passageways are employed to attain the desired result. Furthermore, adjustments necessary to maintain the carburetor in proper working action with changes in temperature, differences in altitude, etc., usually require numerous parts and considerable periodic attention.

In order therefore, to overcome the objections heretofore set forth, our invention contemplates the provision of a carburetor which is exceedingly simple in construction, in that the number of parts is materially reduced, and in that such parts or elements utilized are so simple as to be readily capable of being taken apart, as for cleaning purposes.

Another object of our invention is the provision of a throttle which is arranged to control the proportions of air to fuel as the engine speed is varied, whereby the carburetor works efficiently at idling speeds without further adjustment for running speeds.

Still another object of our invention is the construction of a carburetor which permits the operative elements to be disconnected without breaking the connection

either to the fuel line, or to the intake manifold. This arrangement is advantageous because of the fact that much difficulty is ordinarily experienced in disconnecting a carburetor, due to the inaccessibility of the connecting devices and the liability to strain the fuel line.

In carrying out our invention, we employ what may be called a three-piece construction as embodied in a bowl, a barrel and a throttle, and we so arrange the throttle that correct proportions of fuel and air are secured for all speeds of the engine. This throttle is in effect an automatic mixer and regulator, while it is adapted to be controlled by the operator in the same manner as is the customary butterfly valve. The particular relation between the various ports in the throttle constitutes an important feature of our invention and the relation between the size of the air ports to the fuel ports is an important factor in securing a proper combustible mixture.

The means for accomplishing the above objects will be more fully set forth in the following description which pertains to the drawings, and the essential features of our invention will be summarized in the claims.

In the drawings, Fig. 1 is an elevation partly in section of a carburetor embodying features of our invention; Fig. 2 is a plan view of the carburetor shown in Fig. 1; Fig. 3 is a vertical section taken longitudinally through the carburetor; Fig. 4 is a transverse section taken on the line 4-4 in Fig. 3; and Fig. 5 is a horizontal section taken on the line 5-5 in Fig. 3.

Designating the parts shown in the drawings by the use of reference characters, 10 represents an intake manifold of an internal combustion engine to which our carburetor 95 may be secured; while 11 and 12 represent the air, and fuel intake lines, respectively. The carburetor proper, comprises in general a bowl 13, a barrel 14, and a throttle 15, all of which are castings and as shown in the drawings, are capable of being easily constructed and readily assembled.

The bowl 13 comprises a hollow receptacle, or float chamber, the lower end of which is provided with a valve seat 16 which is adapted to be engaged by a valve 17, which in turn is controlled by the float 18. A passageway 19 extends downwardly from the valve 17

and communicates with a transverse passageway 20, at the outer end of which the fuel intake valve is connected. At the junction of the passageways 19 and 20, we provide a screen 21 and a drain plug 22.

Positioned above the bowl and secured thereto by screws 25, is a barrel 14 which comprises a tubular member having one end as at 26, open to the atmosphere and provided with a choke valve 27, and the other end provided with a flange 28 for enabling the carburetor to be secured to the intake manifold 10. The central portion of the bowl is preferably formed to receive a cylindrical throttle 15 which, as will be hereinafter described, controls not only the correct proportions of air and fuel, but also the quantity of such mixture flowing through the engine. Accordingly, the barrel forms a gas-tight connection as at 28, 29 and 30 with the throttle, while still permitting it to be revolved therein.

The throttle 15 is preferably held in frictional engagement with the barrel by means of a spring retainer 30, one end of which is secured at 31 to the barrel and the other end to the center of the throttle as by means of a projection 32 engaging a corresponding recess 33. The retainer is shown as having a portion thereof adjacent the screw 31, as at 39, extending over the throttle. This extended portion prevents the throttle from being thrown out of the barrel in case of back-firing. The throttle 35 may be equipped with an arm 34 for receiving the control lever 35 which in turn is adapted to be connected with an accelerator lever (not shown) or a hand throttle lever for manual operation. A suitable adjusting screw 36 may be employed for engaging a post 37 and for limiting the angular movement of the throttle, in one direction and a lug 38 may be employed for limiting the movement in the opposite direction.

The throttle 15 constitutes a regulating medium for controlling the fuel admitted to the engine, and for controlling the proportions of air and fuel in such mixture. This is attained by providing an air inlet port 40 which is shown adjacent the end 26 of the barrel 14. The preferred form for constructing this port is shown in Figs. 3 to 5 as comprising a recess having vertical walls 41 and 42, which are of unequal height and are connected by an inclined wall 43. These walls 41 and 42 are so positioned that the longer wall 42 is adjacent the choke valve 27 when the throttle is in closed position, as shown by the dot and dash lines in Fig. 5.

On the opposite side of the air port, we provide another port 44 which as shown in Fig. 1 comprises a circular aperture extending from the bottom nearly to the top of the throttle. The port 44 is so arranged,

that a portion thereof is open even though the throttle is moved to its closed position, and the particular shape of the port, is such as to rapidly increase the area and, accordingly, the quantity of fluid admitted as the throttle is opened. There is however, a further relation between the areas of the ports 40 and 44 in that, as the average height of the trapezoidal opening 40 is diminished (which is occasioned by opening the throttle,) the height of the opening 44 is increased. In this way, the suction within the throttle is relatively increased, and more fluid is drawn through the respective liquid fuel passageways, whereby the mixture which ordinarily would be made leaner as the engine speed is increased is now kept uniform.

As fuel enters the fluid chamber in the bowl 13, it passes laterally and at an oblique angle through the port 50 and enters a passageway 51 which extends upwardly to the top of the bowl and communicates with a passageway 52 in the barrel 14. The passageway 50 extends preferably at an angle of 60° from the bowl and is of such size that the flow of fuel would be sufficient at greatest throttle opening. The passageway 52 is shown as being arcuate in form to correspond with the contour of the barrel adjacent the bowl, and as having a series of minute passageways 53 extending therefrom at an oblique angle and communicating with the interior of the barrel. These passageways as shown in Figs. 4 and 5 are separated and are so arranged as to terminate in that portion of the barrel which is adapted to be traversed by the throttle. In this way, as the throttle is moved in one direction, it successively uncovers the ports to admit a greater quantity of fluid, and conversely, when the throttle is moved in the opposite direction, to restrict the passage of fuel into the barrel. By so proportioning the area of the respective passageways 53 to the area in the port 40, we may obtain a mixture which is operative at all engine speeds for producing most efficient combustion.

To enable the carburetor to be operative while the throttle is moved to the position shown in the dot and dash lines in Fig. 5, we provide an air port 55 which is shown as a rectangular passageway extending through the wall of the throttle, and we have also shown a regulating screw in the form of a plunger 56 for adjusting the area of the passageway 55 in accordance with the engine requirements. A suitable locking means for retaining the plunger in adjusted position is embodied in a cotterpin 57 which extends through the lug 58, and enters a slot 59 in the upper end of the plunger. In this idling position of the throttle, the adjusting screw 36 is so regulated, that the end fuel passageway 54 remains uncovered.

For enabling the carburetor to be choked, we have shown a butterfly valve 27 on the shaft 60 within the barrel 14, and we have shown such valve as being held normally 5 in open position by means of a spring 61, which urges a lug 62 on a bell-crank lever 63 into engagement with a stop 64. A suitable choke lever 65 may be connected to the dashboard for manual operation when desired.

While we have explained the construction of our carburetor as actuated for permitting air to flow across the fuel intake passageways, either through the ports 40 or 55, provision 15 has been made for admitting primary air with liquid fuel through the passageway 51. This is accomplished by extending a passageway 70 in the bowl 13 at an oblique angle with the passageway 51, and by providing 20 another passageway 72 in the barrel which registers with the passageway 71, as shown in Fig. 4. The upper end of the passageway 71 preferably communicates through an oblique passageway 72 with the interior of 25 the barrel adjacent the choke valve. Here, too, a regulating screw 73 is employed for adjusting the amount of air admitted through the auxiliary passageways 70 and 71, and thereby adjusting the quantity of 30 gasoline, thus dispensing with the necessity for a needle valve.

When the engine is operated at slow speeds, that is, when the throttle 15 is in the position shown in dot and dash lines, in 35 Fig. 5, then air, in addition to that flowing through the port 55, is caused to flow through the passageways 72, 71 and 70, and then upward through the passage 51 and into the chamber 52. The air flowing 40 through these passageways may be called the primary air, which acts as an injector to carry liquid fuel from the oblique passageway 50 into the vaporizing chamber. This action is rendered more certain by making 45 the passageway 50 approximately one-half the size of the passageway 51. Ordinarily the air flowing through the passageway 70 is sufficient for producing very efficient combustion at low or idling speeds.

50 The operation of a carburetor constructed according to our invention is as follows:— Assuming that the carburetor is assembled and connected both to the supply line 12 and intake manifold 10, and assuming further that liquid fuel has entered the bowl 13 to the extent permitted by the float-operated valve 17, then when the engine is first started, the rod 65 is pulled, whereupon the choke valve 27 is closed. Accordingly, liquid fuel is then drawn in slugs up to the 55 passageway 15, into the chamber 52, and thence through the oblique passageways 53, and into that portion of the barrel adjacent the throttle 15, from whence it is drawn 60 into the engine. After the engine has been

started, the rod 65 is released, whereupon the valve 27 assumes its normal position by virtue of the spring 61 acting upon it.

To idle the engine, the throttle 15 is moved to the position shown by the dot and dash lines in Fig. 5 wherein passageway 54 is open for permitting fuel to enter the mixing chamber. The air for supporting combustion while the engine is idling, is supplied both through the passageways 71 and 75 55 as heretofore described. The amount of air entering through the port 55 however, may be regulated by means of a threaded plunger 56, while air entering through the 60 passageway 71 may be controlled by means 80 of an adjusting screw 73.

To increase the speed of the engine, the 65 rod 35 is moved to rotate the throttle within the barrel in a contra-clockwise direction, so that the wall 42 successively uncovers the fuel passageways 53, and simultaneously increases the available area in the air port 40, this available air port not 70 however increasing as fast as the port 44. While the engine is operating at a moderate 75 speed, air is being drawn through the passageways 72, 71 and 70, and through the port 55, so long as it remains uncovered by 80 the wall of the barrel. As soon as the 85 throttle is so moved that the port 55 is 90 closed by the wall of the barrel, then practically all of the air for supporting combustion is caused to enter through the main 95 port 40. Since the port 44 is disposed opposite the port 40, then as the throttle is 100 moved to admit a greater quantity of fuel and air into the mixing chamber, it follows that the port 44 is simultaneously opened 105 for allowing the mixture to enter the intake manifold, but since the available air 110 port 44 opens more rapidly than the available port 40 the suction increases out of proportion to the increase of the engine speed. Therefore, as the throttle is opened 115 for admitting a greater quantity of fuel, such fuel is automatically enriched to produce the most efficient combustion.

From the foregoing description, it will 120 be seen that we have provided a carburetor in which the number of operating parts are greatly reduced without rendering the fuel passages inaccessible for maintenance, and that we have provided a carburetor which automatically controls the exact proportions of liquid fuel and air for all engine speeds upon operation of a single throttle lever, and in which the adjustments are reduced to a minimum, and the necessity for controlling the liquid fuel is eliminated.

Having thus described our invention, we 125 claim:—

1. A carburetor having in combination a float chamber, an air conduit carried by the chamber, a throttle disposed within the conduit and comprising a hollow member hav-

ing an air inlet passageway extending upwardly from the bottom thereof and comprising two vertically extending walls and an inclined connecting wall, said hollow member having a discharge passageway also extending upwardly from the bottom thereof, an auxiliary air inlet comprising an opening spaced from the bottom of the member and a vertically extending plunger 10 in threaded engagement with the member for varying the active air of the auxiliary inlet.

2. In a carburetor the combination with a liquid container, of an air conduit carried thereby, a fuel passageway extending laterally and upwardly from the container and terminating in a plurality of minute discharge passageways adjacent said conduit, a primary air passageway extending 20 downwardly through the fuel passageway below the liquid level in said container and a manually operable closure for said discharge passageways, said closure having an inlet for secondary air.

25 3. A carburetor having in combination, a float chamber, an air conduit carried by the chamber, a throttle disposed within said conduit and having two air inlet passageways communicating with the air conduit and a discharge passageway for combustible mixture, a fuel passageway leading through the float chamber and terminating adjacent the throttle in a plurality of spaced conduits, one of the air inlet 30 passageways having its upper edge extend-

ing obliquely, the highest point being forward when the throttle is being opened, and the other air inlet comprising an aperture spaced above the bottom of the throttle and arranged to be opened when the first mentioned inlet is closed, and said discharge passageway being adapted to be opened when either of the inlet passageways are opened.

4. In a carburetor, the combination with 45 a float chamber, of an air conduit positioned on said chamber and having a cylindrical opening extending transversely thereof, the axis of said opening being in alignment with the axis of said float chamber, a vertically extending fuel passageway leading upwardly from the float chamber and terminating in a plurality of spaced apertures in the wall surrounding the conduit, a throttle having a shoulder engaging the top 50 of the conduit and having a depending wall disposed across said conduit, said wall having two air inlet passageways and one air discharge passageway therein so positioned as to be opened whenever either or 55 both of the inlet passageways are opened, the discharge passageway and inlet passageways being so shaped that the discharge passageway will be progressively opened at a greater rate than the inlet passageways 60 when the throttle is being opened.

In testimony whereof, we hereunto affix our signatures.

CAREL T. TORRESEN.
CHARLES G. ROTH.
